UNITED STATES PATENT OFFICE

132,638

DESIGN FOR A COMBINATION DESK UNIT

Jacques Martial, Great Neck, N. Y., assignor to
The Esterbrook Steel Pen Manufacturing Co.,
Camden, N. J., a corporation of New Jersey

Application June 21, 1941, Serial No. 101,605

Term of patent 14 years

To all whom it may concern:

Be it known that I, Jacques Martial, a citizen of the United States and a resident of 8 Welwyn Road, Great Neck, N. Y., whose post office address is care The Esterbrook Steel Pen Manufacturing Co., Delaware Avenue and Cooper Street, Camden, New Jersey, have invented a new, original, and ornamental Design for a Combination Desk Unit, of which the following is a specification; reference being had to the accompanying drawing, forming a part thereof.

Fig. 2 is a plan view of the combination desk unit shown in Fig. 1.

Fig. 3 is a front elevation of the combination desk unit shown in Fig. 1.

Fig. 4 is a side elevation of the combination desk unit shown in Fig. 1.

I claim:

The ornamental design for a combination desk unit substantially as shown in the accompanying drawing.

JACQUES MARTIAL.
